ELECTRICAL APPARATUS

Prescott D. Crout, Boston, Mass., assignor to
 Raytheon Manufacturing Company, Newton,
 Mass., a corporation of Delaware

Application September 6, 1934, Serial No. 742,913

8 Claims. (Cl. 171—242)

This invention relates to an electrical apparatus.

An object of this invention is to devise a novel movable reactor-bar control arrangement for the apparatus.

The foregoing and other objects of my invention will be best understood from the following exemplification thereof, reference being had to the accompanying diagrammatic drawings, wherein:

Fig. 1 is a side view of the apparatus with portions broken away to show the interior thereof;

Fig. 2 is an end view of the apparatus;

Fig. 3 is a section taken along lines 3—3 of Fig. 1;

Fig. 4 is a top view of a combined transformer and inductance control unit which is incorporated in the apparatus, the top baffle plate being broken away to show the underlying structure;

Fig. 5 is a side view of the device shown in Fig. 4, the side baffle plates being broken away to show the underlying coils;

Fig. 6 is a section taken along line 6—6 of Fig. 4;

Fig. 7 is a detail of the indicator dial-operating mechanism with parts broken away to show the underlying structure; and

Fig. 8 is a diagram of the circuit arrangements of the apparatus.

I have devised a novel electric arc-welding system comprising a gaseous discharge rectifier, a transformer for supplying power to said rectifier, and an inductance control device in the primary circuit of said transformer for controlling the output current of the rectifier which is adapted to feed an electric welding arc. This system is described and claimed in my Patent No. 1,928,848 dated October 3, 1933. In the present invention the various elements of such a system are mounted in a compact and unitary arrangement. In the drawings, 1 represents a frame within which is mounted a unitary power and control device 2 consisting of a transformer 3 and an inductance control unit 4. On top of the frame 1 is mounted the tube support 5 within which is supported the rectifier tube 6. This tube is preferably of the construction as shown in the copending application of Spencer and Marshall, Serial No. 729,101, filed June 5, 1934, although any other suitable rectifier could be used. On the frame are also mounted the front wall 7, carrying various terminals, indicating and adjusting members, and the rear wall 8 carrying the ventilating fan 9. A protecting screen 9' covers the air-inlet opening in the rear wall 8. A cover

10 carried by the front and rear walls 7 and 8 encloses the space between the walls 7 and 8 and the frame 1 within which the tube 6 is supported. Handles 128 are secured to the upper wall of cover 10, but are free to rotate therein. 5 These handles 128 are threaded at their inner ends and are adapted to engage corresponding threads in two blocks 129 fastened to the front and rear walls 7 and 8, respectively. In this way cover 10 may be securely fastened in place 10 on the frame 1 or may be readily removed for adjustment, inspection or repair of the internal assembly within the frame 1.

The structure is preferably provided with wheels 11, 12 and 13 in order that it may easily 15 be moved from place to place. The front wheel 11 is mounted on an axle 14 carried by a yoke 15. The yoke 15 is carried at the lower end of a supporting stud 16, the upper end of which passes rotatably through a bushing in the upper 20 wall of frame 1. A spring 18 is placed between the upper side of the yoke 15 and the upper wall of the frame 1. The upper end of said stud 16 has rigidly fastened to it the arm 17. The outer end of arm 17 is formed as a yoke between the 25 arms of which is rotatably mounted on a shaft 18 the lower end of the handle 19. The upper end of the handle is provided with a cross-bar 20 in order to provide a convenient means whereby the operator can grasp the handle 19 in order to 30 push or pull the apparatus to the desired location. On the upper side of the front wall 7 is mounted a catch 21 which engages the bar 20 and holds the handle 19 in the position shown when said handle is not in use. The catch 21 is preferably biased in its retaining position by means of a spring (not shown). The rear wheels 12 and 13 are supported on shafts 22 and 23 carried by supporting arms 24 and 25, respectively. Each arm 24 and 25 is formed with a bifurcated portion at one end thereof, the wheels 12 and 13 being supported between the arms of said bifurcated portion. The supporting arms 24 and 25 are rotatably mounted at approximately the center thereof by shafts 26. At the rear end of 45 each of said arms is connected a spring 27, the upper end of which is connected to the top rear portion of the frame 1. In this manner each of the wheels 12 and 13 is supported by a cantilever arrangement. The wheels 11, 12 and 13 are also 50 each preferably supplied with rubber tires 28. In order to enable the machine to be hoisted to any desired position, the front and rear walls 7 and 8 are each supplied with two hoisting rings 130.

The unitary power and control device 2 is shown most clearly in Figs. 4, 5 and 6. In the particular embodiment which I have illustrated, the transformer 3 has a three-phase primary and a six-phase secondary while the inductance control unit 4 has three inductance coils in series with the three-phase line feeding the primary of the transformer. The primary and secondary coils of the transformer and the inductance coils are all mounted upon a combined core structure 29 having three legs 30, each of which carries a primary coil and a secondary coil with a center tap. Terminal conductors 31 to 36, inclusive, are provided to establish the connection to the ends 15 of the primary coils. The ends of the secondary coils are brought out to terminal conductors 37 to 42, inclusive, and the center taps of the secondary coils are brought out to conductors 43, 44 and 45. The combined core unit 29 is also provided 20 with three additional legs 46, 47 and 48 upon which the three inductance control coils 49, 50 and 51 are respectively mounted. The ends of the coils 49, 50 and 51 are brought out to terminal conductors 52 to 57, inclusive, whereby the proper 25 connection may be established to each of these coils. The magnetic circuit for the legs 30 is completed by a yoke 58 at the rear end thereof and by a yoke 59 at the other end thereof. The yoke 59 also interconnects the three legs 46, 47 and 48 of the inductance control. A movable reactor bar 60 is disposed adjacent the outer ends of the legs 46, 47 and 48 which form the pole faces of these legs. By varying the distance 30 between the reactor bar and the pole faces, the inductance of the coils 49, 50 and 51 is varied. The core member 29 and the coils mounted thereon are rigidly clamped between the upper and lower sections of a frame 61 by means of 35 bolts 62. The frame 61 may be made of a light non-magnetic metal, such as aluminum. The movable reactor bar 60 has clamped to its upper and lower sides the two plates 65 and 66 which are held firmly in place by means of bolts 67. The laminations of the bar 60 are thus firmly 40 clamped together. At each end of the bar 60 is provided a block 68. Each block has a pair of trunnions 69 formed in its upper and lower side. These trunnions are received in the upper and 45 lower plates 65 and 66, respectively, so as to allow each block 68 to rotate to some degree about the axis of trunnions 69. Each block 68 is provided with a bore through which passes a rod 70. The rod 70 is securely fastened against 50 rotation in the bore of block 68 by suitable means, such as a taper pin or key, and is provided at its end with a nut 71 which prevents the bar 60 and its blocks 68 from being pulled off the rods 70. Each rod 70 is supported in 55 position on the frame member 61 by two bushings 72 and 72' held firmly on the frame member 61. Each rod 70 is free to slide in its bushings. At the end where the bushings are supported, the frame member 61 is split so as to provide 60 upper and lower clamping arms 73 and 74 for said bushings. Bolts 75 firmly clamp the arms 73 and 74 around the bushings, whereby the bushings, the rods 70 and their associated structure are retained in their proper positions. In order 65 to vary the position of bar 60, each rod 70 is threaded throughout substantially its entire length. An internally-threaded sleeve 76 is provided on each rod 70 between the two bushings 72 and 72'. The internal threads of the sleeve 75 fit the external threads of the rod 70, and

thus the rotation of the sleeve 76 will move the rod 70 forward or back with respect to the frame 61 depending upon the direction in which the sleeve 76 is rotated. In order to rotate the sleeves 76, each sleeve is provided with a sprocket 77 (see Fig. 3), and a single chain 78 passes around and engages both sprockets 77. A third sprocket 79 is mounted on a shaft 80 in the front wall 7, and may be rotated by an actuating wheel 81 mounted on the shaft 80 in front of the wall 7. The chain 78 also passes around and engages sprocket 79. By having the single chain 78 engage both sprockets 77, both rods 70 will be moved in synchronism when the actuating handle 81 is rotated. Thus the ends of the bar 60 will 15 always be parallel to the pole faces of the legs 46, 47 and 48 in any position to which the bar 60 is moved by the above-mentioned mechanism. Each rod 70 is provided with an adjustable stop 82 so that the spacing between the pole faces 20 of the legs 46, 47 and 48 and the bar 60 in its innermost position may be definitely predetermined. The arrangement of the clamping arms 73 and 74 affords a convenient way of assembling the reactor bar 60 and its associated structure in 25 proper position on the frame 61.

In the above arrangement the ends 70 could be rotatable and the sleeves 76 held stationary. In that case the sprockets 77 would be mounted 30 on the ends 70.

In order to afford the operator a convenient way of setting the bar 60 in the proper position, the shaft 80 has geared thereto an indicating disk 124. This disk 124 is mounted on a stud 125 rotatably mounted in the front wall 7. The disk 124 may be provided with any suitable markings, but is preferably calibrated in load amperes. The wall 7 is provided with a window 126 through which the operator may observe the 40 markings on the disk 124. The window is preferably provided with indicating arrows 127. The machine is usually adapted to be used with various kinds of welding rods which operate on two different voltage ranges. The current through 45 the load for each setting of the bar 60 will be somewhat different at these two voltage ranges. Thus the disk 124 preferably carries two calibrations, one for each voltage range, and the window 126 has correspondingly two indicating arrows 50 127.

The problem of supporting a movable reactor bar disposed adjacent a magnetic core excited by current has been a particularly troublesome one. Attempts have been made in various other relationships to support such a movable reactor bar, but such previous efforts have resulted in very severe chattering of the reactor bar and its associated structure. Inasmuch as any commercial application should be relatively quiet, such 60 excessive chattering is very objectionable. By my present invention I have devised an arrangement whereby a movable reactor bar may be supported at any of its adjusted positions without chattering. Whenever a reactor bar is supported with a spacing between the pole faces of the reactor core legs and the reactor bar and the reactor core is energized, there is a force which tends to move the reactor bar toward the core. In any system with a movable reactor bar, there must be 70 a mechanical structure which will hold the reactor bar in place against the action of the magnetic forces. Such mechanical structure constitutes an elastic system. In any such system of support for the reactor bar, there ordinarily 75

exists a plurality of members with contacting surfaces which can leave each other. This separation may be slight, but if it occurs in the presence of the vibration of parts, chattering will result. When I use the term "chattering", I means the action produced when such separation and subsequent engagement of such surfaces takes place. In addition to the chattering, the surfaces, upon coming in contact with each other after separation, will cause impact upon the members of the supporting system, and such impact might seriously damage the structure after a comparatively short time.

I have found that when a reactor bar is supported, as I have indicated above, and the core is energized by an alternating current, the reactor bar is subjected to a plurality of forces. First of all there may be a constant translatory force tending to cause the reactor bar to approach the core. Ordinarily in a system where the legs are symmetrical and similarly energized, this constant translatory force acts over the central point of the legs. There also may be a constant torque on the reactor bar in the plane of the reactor legs. In the usual case mentioned above, this torque is ordinarily zero. There also may be an alternating translatory force tending to move the reactor bar toward and away from the pole faces of the reactor legs. In the case mentioned above, this alternating translatory force usually acts over the central point of the legs. There also may be an alternating torque acting in the plane of the reactor legs. If, for example, the reactor is a two-legged, double-air gap, single-phase reactor, the forces acting are the constant translatory force and the alternating translatory force, both of the torques mentioned above vanishing. If it is a three-legged, three-air gap, three-phase reactor, such as described, for example, in the present application, the force system comprises the constant translatory force and the alternating torque. The above conditions describe the steady state of the reactor. If the amplitude of the current energizing the reactor is permitted to vary, or if other transient conditions occur, other forces may exist. These forces likewise can be split up into constant and alternating forces. In any such system I have found that in order to eliminate chattering, the alternating displacement amplitudes produced by the above-mentioned alternating forces must be smaller than the displacements due to the constant forces. Ordinarily in any system in which the reactor bar is supported by a supporting structure, there does exist under some conditions alternating displacements which are greater than the displacement due to the constant forces. In order to make sure that such a condition shall not exist in order to avoid any chattering whatsoever, I provide an additional constant force tending to move the reactor bar toward the pole faces of the core, and I make the magnitude of this additional unidirectional force great enough to satisfy the above requirement under all conditions to which the device may be subjected during operation. In the particular embodiment shown in the drawings I provide this additional force by providing springs 63 and 64 which exert a pull on the movable bar 60, tending to move it toward the pole faces of the legs 46, 47 and 48. In addition to the various forces which have been discussed above, there also may exist some back-lash between the various elements which constitute the reactor bar and its supporting

structure. The additional constant force which I exert on the reactor bar by the springs 63 and 64 is made sufficiently great so that the requirements set forth above are satisfied over and above the forces necessary to take up all back-lash.

In order to provide means for attaching the springs 63 and 64 to the reactor bar 60, the plates 65 and 66 are extended beyond the frame 61 and carry at each end thereof a ball 83 whose ends 84 and 85 project freely through openings in the plates 65 and 66, respectively. These ends are retained in place by some convenient means, such as cotter pins 86. One end of each spring 63 and 64 is hooked over the middle portion of the respective ball 83, and the other end of each of said springs is held in place on the frame 61 by means of a retaining rod 87. Each rod 87 passes freely through a stud 88 formed integrally with the frame 61. Each rod 87 is provided with an eyelet 89 through which the other end of the respective spring 63 or 64 can be hooked. Each rod 87 is threaded at its outer end and provided with a nut 90.

The unitary power and control device 2 is provided with four mounting brackets 91. Two of these brackets are mounted on the studs 88. Two additional studs 92 are provided upon which the other two brackets 91 are mounted. A bushing of soft rubber 93 is interposed between each bracket 91 and its associated stud in order to prevent any vibration set up in the combined transformer and inductance control unit from reaching the frame 1. The unit is secured in the frame 1 by bolts 94 which pass through the frame 1 and engage the brackets 91, as shown in Fig. 1. The only other connection between the frame 1 and the device 2 is the transmission system between the actuating wheel 81 and the bar 60. The chain 78 interposed in this transmission system constitutes a flexible member through which no vibration from the device 2 can be transmitted to the frame 1.

I have arranged the various parts of my system so that a fan with a rating sufficient to cool the transformer and inductance element may be used to cool the tube in addition. The tube 6 is provided with a condensing chamber 131 from which a fairly large amount of heat must be removed. This condensing chamber 131 is disposed directly in the path of the blast of air blown into the machine by the fan 9, and is cooled thereby. Some of the velocity head created by the fan 9 is dissipated by the turbulence around the tube 6. This turbulence, however, creates sufficient circulation of air around the tube 6 to produce the desired cooling thereof. The remaining portion of the velocity head becomes a pressure head within the chamber enclosed by the cover 10. The cover 10 when fastened down by the handles 128 fits the front and back walls 1 and 8 sufficiently close so that the air can escape from the chamber within the cover 10 only through the opening around the transformer 3 and the inductance-controlling unit 4. The pressure head created in the chamber within the cover 10 is converted into a velocity head around the members 3 and 4, and air blows past them at a sufficient rate to produce adequate cooling of these members. Thus we see that the air blown into the machine by the fan 9 enters with a velocity head sufficiently to cool the tube 6 and also to build up a pressure head in the chamber within the cover 10, which pressure head is again converted into a velocity 75

head around the members 3 and 4, whereby these members likewise are cooled.

In the arrangement shown in Figs. 4, 5 and 6, the various coils and core members are constructed in such a manner that when assembled in the apparatus they are capable of being easily cooled by the air which is blown past them by the pressure head under the cover 10. The coils on the legs 30 are spaced apart from each other and the surfaces are curved in such a manner as to provide a plurality of air ducts 132 around them. The coils 49, 50 and 51 are likewise disposed in a similar manner as to provide a plurality of air ducts 133. In order to confine the cooling air to the proper channels in the manner as will be described below, the portion of the frame 61 which is not filled by the various coils and the air ducts 132 and 133 is covered by a baffle plate 134, preferably of a light insulating board material. It is desirable to cool the pole faces of the legs 46, 47 and 48 and the inner face of the movable reactor bar 60. In order that these surfaces may be properly cooled, I form the baffle plate 134 with a plurality of air ducts 136, 137 and 138 disposed adjacent the faces of the legs 46, 47 and 48, respectively. The baffle plate may be conveniently retained in place by fastening means, such as bolts 139 and a screw 139'.

In order to confine the air to the proper channels adjacent the outside of the transformer coils on the outer legs of the transformer, baffle plates 140 are provided on both sides of the transformer. Similar baffle plates 141 are provided for the reactor coils. Additional baffle plates 142 are provided to direct cooling air past the sides of the core between the transformer and the reactor.

The various elements described are electrically connected in a suitable electrical circuit, such as that shown in Fig. 11. Three line conductors 40 L₁, L₂ and L₃ from a three-phase line are connected to the main contactor 143 which serves to connect the three line conductors L₁, L₂ and L₃ to the three conductors 144, 145 and 146 leading to the three terminals 52, 54 and 56 of the three reactor coils 49, 50 and 51. The three primary coils 149, 150 and 151 of the transformer 3 are preferably connected in a delta connection, the three corners of which are connected to the terminals 53, 55 and 57 of the reactor coils 49, 50 and 51. The three center taps of the secondary coils are connected together to the common conductor 152 which is in turn connected to contact 153 on the reversing switch 154. The six outer terminals 37 to 42, inclusive, of the secondary coils are connected to the six anodes 155 of the rectifier 6. The cathode 156 of the rectifier 6 is connected through a shunt 157 to contact 158 on the reversing switch 154. The reversing switch 154 is provided with two additional contacts 178 and 179 connected to two external binding posts 180 and 181 mounted on the front wall 7, as shown in Figs. 1 and 2. A pair of movable contact arms 182 and 183 selectively connect contacts 153 and 158 either to contacts 178 and 179, respectively, or vice versa. The movable contact arms may be moved to either position by the operating lever 184, shown most clearly in Fig. 2. The lever 184 is mounted on a stub shaft 184' which passes rotatably through the front wall 7, and has secured to its inner end the insulating plate 185. The insulating plate 185 carries the two contact arms 182 and 183. By shifting the operating lever 184 from one position to another, the polarity of the binding posts 180 and 181 may be reversed. Thus 75 during operation the operator may readily reverse

the polarity of his welding electrode and the piece to be welded without disconnecting the conductors connected to binding posts 180 and 181. The binding posts 180 and 181, the stationary contacts of the switch 154, together with their associated conductors, are mounted on the insulating plate 189' and are thus insulated from wall 7.

As is set forth in my Patent No. 1,928,848, it is desirable to eliminate all inductance in the load circuit. Since the wall 7 is usually made of iron and the load circuit passes through the wall 7 by means of the binding posts 180 and 181, the wall 7 would ordinarily form a closed magnetic path around the conductors in the load circuit, and might introduce some self-inductance. In order to eliminate this effect, a slot 186 is cut through the wall 7 between the binding posts 180 and 181. This interrupts the otherwise complete magnetic path around each of said binding posts, and thus substantially prevents the introduction of any appreciable amount of self-inductance at this point.

The contactor 143 is provided with a closing and holding coil 159 controlled by two manual "start" and "stop" pushbuttons 160 and 161. The starting circuit for the coil 159 extends from the line L₃ through the coil 159, the protective contacts 162, the contacts of the "stop" button 161 (normally closed), the contacts of the "start" button 160 (normally open), and then to the line 30 L₁. Thus, upon closing the contacts of the "start" button 160, the circuit is closed and the coil 159 closes the contactor 143. Upon closing, the contactor 143 also closes the maintaining contacts 163 connected across the contacts of the 35 "start" button 160 so that the circuit for coil 159 is maintained even after "start" button 160 is released to its open position. In order to open the contactor 143, the "stop" button 161 is depressed, which opens its contacts. This in turn 40 opens the circuit for the coil 159 and allows the contactor 143 and the maintaining contacts 163 to open.

The protective contacts 162 provide protection for the machine against overload and fan failure. 45 The fan 9 is connected to the three conductors 144, 145 and 146. In two of these conductors, for example conductors 144 and 145, are connected heating elements 164 and 165, respectively. Each heating element 164 and 165, as its temperature 50 rises, tends to open the contacts 162. Since the current through the elements 164 and 165 varies with the load, the temperatures of these elements vary with the load on the machine. The device is so calibrated that upon a sustained overload, the 55 temperature of the heating elements 164 and 165 rises sufficiently to open the contacts 162. This in turn deenergizes the coil 159 and opens the main contactor 143. The inherent time delay in the heating elements 164 and 165 permits temporary overloads to occur without opening the contacts 162. Since the machine is built to withstand large temporary overloads, this operator is desirable.

A tube 167 is provided which extends from the 65 chamber within the cover 10 to a point adjacent the heating element 164. The pressure head of air created by the fan 9 in the chamber within the cover 10 causes air to blow through the tube 167 onto the heating element 164. This air cools 70 the element 164 so that normally it will not open the contacts 162. If, however, for any reason whatsoever the fan 9 fails to operate, the pressure head in the machine disappears and the air stops flowing through tube 167. The element 164 75

is so chosen that the current flowing heats it sufficiently to open the contacts 162, thus shutting off the machine. Since the failure of fan 9 would tend to overheat the machine and since such overheating occurs only after the fan has ceased to operate for some length of time, the heating element 164 may be designed to heat up slowly and open the contacts 162 at the necessary time. The machine at heavy loads would tend to heat up more rapidly than at light loads. This factor is taken care of by the fact that the current through the element 164 is a function of load current. Thus as the load increases, the element 164 heats up faster and tends to open the contacts 162 sooner.

The cathode 156 of the tube 6 is usually provided with a separate heating filament 168. This filament is supplied with heating current from a filament transformer 169 which may be mounted on the frame 1 within the cover 10, as shown in Fig. 1. The filament transformer 169 is supplied with current by the two conductors 170 and 171 connected to the two conductors 144 and 145. Fuses 172 and 173 may be interposed in the conductors 170 and 171, respectively. When the heating current for the thermionic cathode 156 is turned on, it is usually advisable to wait until the cathode is heated sufficiently to emit enough electrons to properly start the discharge within the tube 6 before a load is placed on the tube. In order to indicate to the operator when the cathode is at the proper temperature to start welding, a lamp 174 is connected from one of the anodes 155 to the cathode as, for example, by a conductor connected to one side of the shunt 157. Interposed in this circuit of the lamp 174 is a thermostat 175. This thermostat 175 is open when cold. A heating element 176 for the thermostat 175 is connected across the secondary of the filament transformer 169. Thus when the filament transformer is energized and starts heating the filament 168 at the same time it starts heating the heating element 176. When the cathode 156 reaches the proper temperature, the element 176 heats up sufficiently to close the contacts of the thermostat 175. This closes the circuit for the lamp 174 from the terminal 40, through the thermostat 175, the lamp 174, the cathode 156, the discharge space through the tube 6, the anode 155 connected to terminal 39 and back to the terminal 39. The coil 39-40 impresses a voltage on the said circuit, and causes a small discharge to occur between the cathode and one of the anodes, thus lighting the lamp 174. This indicates to the operator that the tube is ready to operate. The fact that the discharge space in the tube is included in the circuit of the lamp 174 is an additional way of determining whether the tube is ready for operation. The fact that the lamp 174 lights shows that the cathode 156 is emitting a considerable amount of thermionic electrons, in order to support the discharge to light the lamp 174. This shows that the thermionic emission is sufficient to start the main discharge in the tube.

The arrangement of lamp 174 also comprises a special starting device for the rectifier tube 6. During operation the voltage from the neutral conductor 152 to one of the secondary coil terminals is impressed between the cathode and each anode. In starting it is desirable to increase this voltage in order to insure the initiation of the discharge. The circuit of the lamp 174 connects the cathode 156 directly to one of the anodes 155. Before the discharge starts, no current

flows in the lamp circuit and no voltage drop occurs in this circuit. Thus the cathode is at the same potential as said anode. At that time the voltage between the cathode 156 and the anode 155 connected to the terminal 39 is the total voltage across coil 39-40. This is double the normal running voltage and insures a starting of the discharge between the cathode 156 and the anode 155 connected to the terminal 39. Once this discharge is started, the current flowing through the lamp 174 produces a voltage drop which tends to return the potential of the cathode to that of the neutral point of the secondary winding of the transformer 3. The initiation of the discharge between the cathode 156 and the anode 155 connected to the terminal 39 enables the discharges to each of the other anodes to occur at the normal running voltage. To insure the operation of this starting circuit even if lamp 174 burns out, a resistance 177 is connected in parallel with the lamp 174.

An ammeter 187 is connected across the shunt 157 to indicate the current flowing in the load circuit. A voltmeter 188 is connected between the contacts 158 and 153 on the reversing switch 154. These constitute substantially the output terminals of the machine, and thus voltmeter 153 indicates the voltage across the load.

The control buttons 160 and 161, the lamp 174, the resistance 177, the ammeter 187, and the voltmeter 188 are all conveniently mounted on the front wall 7 as shown in Figs. 2 and 3. The lamp 174 has a red lens 189 disposed in front of it so that a red light glows on the front wall 7 when the machine is ready to operate.

Of course it is to be understood that this invention is not limited to the particular details of the arrangement as described above as many equivalents will suggest themselves to those skilled in the art. Also various of the different parts of the machine may be used in other relationships. For example, the invention disclosed with respect to the movable reactor bar 60 may be utilized in any device where a magnetic member is to be moved in order to vary an air gap. Likewise the ventilating principle for the machine can be used in other devices aside from a welding machine. Various other changes and uses in and for the various novel parts of my machine will readily suggest themselves. It is accordingly desired that the appended claims be given a broad interpretation commensurate with the scope of the invention within the art.

What is claimed is:

1. In a magnetic apparatus, a magnetic core, means for setting up a magnetic flux in said core, said magnetic core having a variable air gap between a pole face and a movable magnetic bar, supporting means for supporting said magnetic bar spaced from said pole face, and additional means for exerting on said magnetic bar a unidirectional force tending to move said bar toward said pole face, the magnitude of said unidirectional force being great enough to prevent chattering.

2. In a magnetic apparatus, a magnetic core, means for setting up a magnetic flux in said core, said magnetic core having a variable air gap between a pole face and a movable magnetic bar, supporting means for supporting said magnetic bar spaced from said pole face, and additional means for exerting on said magnetic bar a unidirectional force tending to move said bar toward said pole face, the magnitude of said unidirectional force being great enough to prevent

chattering, said supporting means being adjustable for varying the distance between said magnetic bar and said pole face.

3. In a magnetic apparatus, a magnetic core, means for setting up a magnetic flux in said core, said core having a plurality of legs with pole faces thereon, a movable magnetic bar, supporting means for supporting said magnetic bar spaced from said pole faces, and additional means for exerting on said magnetic bar a unidirectional force tending to move said bar toward said pole faces, the magnitude of said unidirectional force being great enough to prevent chattering, said supporting means being adjustable for varying the distance between said magnetic bar and said pole faces.

4. In a magnetic apparatus, a magnetic core, means for setting up a magnetic flux in said core, said core having a plurality of legs with pole faces thereon, a movable magnetic bar, supporting means for supporting said magnetic bar spaced from said pole faces, spring means for exerting on said magnetic bar a unidirectional force tending to move said bar toward said pole faces, the magnitude of said unidirectional force being great enough to prevent chattering, said supporting means being adjustable for varying the distance between said magnetic bar and said pole faces.

5. In a magnetic apparatus, a magnetic core, means for setting up a magnetic flux in said core, said core having a plurality of legs with pole faces thereon, a movable magnetic bar, supporting means for supporting said magnetic bar spaced from said pole faces, said supporting means comprising a plurality of rods secured to said magnetic bar at spaced points along said bar, said rods being threaded along a substantial length, each rod carrying an internally-threaded nut engaging the threads on its respective rod, means for mounting said nuts at a fixed distance from said magnetic core, said nuts and rods being relatively rotatable, sprocket means for each associated nut and rod for causing relative rotation between them, a single chain engaging all of said sprocket means, means for moving said chain, and additional means for exerting on said magnetic bar a unidirectional force tending to move said bar toward said pole faces, the magnitude of said unidirectional force being great enough to prevent chattering.

6. In a magnetic apparatus, a magnetic core, means for setting up a magnetic flux in said core, said core having a plurality of legs with pole

faces thereon, a movable magnetic bar, supporting means for supporting said magnetic bar spaced from said pole faces, said supporting means comprising a plurality of rods secured to said magnetic bar at spaced points along said bar, said rods being threaded along a substantial length, each rod carrying an internally-threaded nut engaging the threads on its respective rod, means for mounting said nuts at a fixed distance from said magnetic core, said nuts and rods being relatively rotatable, means for causing relative rotation between said nuts and rods in synchronism, and additional means for exerting on said magnetic bar a unidirectional force tending to move said bar toward said pole faces, the magnitude of said unidirectional force being great enough to prevent chattering.

7. In a magnetic apparatus, a magnetic core, means for setting up a magnetic flux in said core, said core having a plurality of legs with pole faces thereon, a movable magnetic bar, supporting means for supporting said magnetic bar spaced from said pole faces, said supporting means comprising a plurality of rods secured to said magnetic bar at spaced points along said bar, said rods being threaded along a substantial length, each rod carrying an internally-threaded nut engaging the threads on its respective rod, means for mounting said nuts at a fixed distance from said magnetic core, said nuts and rods being relatively rotatable, sprocket means for each associated nut and rod for causing relative rotation between them, a single chain engaging all of said sprocket means, means for moving said chain, and spring means for exerting on said magnetic bar a unidirectional force tending to move said bar toward said pole faces, the magnitude of said unidirectional force being great enough to prevent chattering.

8. In a magnetic apparatus, a magnetic core, means for setting up a magnetic flux in said core, said core having a plurality of legs with pole faces thereon, a movable magnetic bar, a plurality of supporting means at different points on said magnetic bar, means for moving all of said supporting means in synchronism to move said magnetic bar toward and away from said pole faces, and additional means for exerting on said magnetic bar a unidirectional force tending to move said bar toward said pole faces, the magnitude of said unidirectional force being great enough to prevent chattering.

PREScott D. CROUT.
